UNITED STATES PATENT OFFICE.

FRANCIS A. McDONALD, OF LAMBERTVILLE, NEW JERSEY, ASSIGNOR TO LAMBERTVILLE RUBBER COMPANY, OF LAMBERTVILLE, NEW JERSEY, A CORPORATION OF NEW JERSEY.

DESIGN FOR A SOLE FOR SHOES.

Application filed September 18, 1922. Serial No. 3,747. Term of patent 7 years.

To all whom it may concern:

Be it known that I, FRANCIS A. McDONALD, a citizen of the United States, residing at Lambertville, in the county of Hunterdon and State of New Jersey, have invented a new, original, and ornamental Design for a Sole for Shoes, of which the following is a specification, reference being had to the accompanying drawing, forming part thereof, in which—

Figure 1 is a face view of a sole for shoes, showing my new design;

Figure 2 is a sectional view on the line 2—2, Fig. 1.

I claim:

The ornamental design for a sole for shoes, as shown.

FRANCIS A. McDONALD.
